Patented Apr. 8, 1924.

UNITED STATES PATENT OFFICE.

CHARLES O. SCHELLENBACH, OF CINCINNATI, OHIO.

REAMER.

Application filed May 3, 1921. Serial No. 466,509.

To all whom it may concern:

Be it known that I, CHARLES O. SCHELLENBACH, a citizen of the United States, and residing at Cincinnati, in the county of Hamilton and State of Ohio, have invented a new and useful Improvement in a Reamer, of which the following specification is a full disclosure.

My invention relates to an expanding removable blade reamer, in which the blades are longitudinally flexed for reamer expansion.

An object of the invention is to provide a reamer with removable blades, placed longitudinally of the reamer body, to be uniformly flexed longitudinally for an expansion by the expanding member disposed parallel with and centrally between the blade, and a thrust transmitting member for each blade cooperating with the expanding member and at an angle thereto.

Another object of the invention is to provide a removable blade expanding reamer wherein the expansion is produced by longitudinally flexing the blades, the parts being compactly arranged of simple and durable construction, for an increased degree of reamer expansion.

Other objects and advantages will be more fully revealed in the following description of the drawings, forming a part of this specification, and in the drawings of like characters of reference denote corresponding parts throughout the several views, of which:

Fig. 1 is a side view of the reamer with the shank end omitted, which may be of any length and formed with a squared end or otherwise to meet the commercial requirement for chucking the tool.

Fig. 2 is a section through the reamer on line 2, 2, Fig. 2, showing the blade in its non-expanded position.

Fig. 3 is a section on line 3, 3, Fig. 2.

Fig. 4 is a section, similar to Fig. 2, showing the blade in an expanded position.

Fig. 5 is a section taken on line 5, 5, Fig. 4.

Referring to the drawings, 1 indicates the tool body of round bar form, having a central longitudinal bore 2, extending from one end, with the forward end portion 3 threaded for receiving the threaded end 4 of the expanding mandrel 5. The body 55 peripherally is provided with a series or plurality of longitudinal cutter blade re-

ceiving slots 6, the number being optional, and determined by the size and class of work for which the reamer is intended. In the form shown, the blade slots are of uniform dimension and spaced about the body, rendering the blades interchangeable since all are of duplicate construction. A detailed description of such duplicate parts therefore will be confined to the singular.

The blade slot preferably is disposed with its longitudinal axis diametric with the axis of the base 2 or expander. The blade slot has its opposite ends rounded for convenience in manufacturing. The body adjacent each end of the blade slot is radially counterbored to receive the blade clamping screws 7, 7, the heads of the screws projecting into the blade slot for engagement respectively with opposite ends of the cutter blade 8 seated or nested within the slot. The blade 8 in outline corresponds to the outline of the slot, having its opposite rounded ends notched to provide the shoulders 9, 9, for engagement beneath the heads of the clamping screws 7, 7. It is obvious that other means may be employed for anchoring the opposite ends of the blade within the reamer body, although the means herein employed are of simple and efficient construction, providing for a quick and convenient insertion and removal of the blades.

The blades illustrated are of the plural cutting edge type, providing two cutting edges 10, 10, with a longitudinal clearance groove 11, between them and with the cutting edges extending only a portion of the blade length. The under side of the blade presents a plane surface and is transversely grooved at an intermediate portion across its width, as at 12, for reducing the body thickness of the blade at such portion, rendering the blade more flexible and increasing its degree of longitudinal flexibility. For flexing and expanding the blade, 100 the expander rod or mandrel 5 is provided with a conical portion or end 13, as a wedge element, engaging a ball 14 socketed within a radial bore or opening 15, through the wall of the reamer body between the central bore and blade slot, the ball furnishing a universal connection between the conical portion of the expander and the base surface of the blade, whereby the ball is moved or adjusted radially upon 110 adjusting the expander for flexing the blade. To expand the blade, the expander

is screwed or threaded within the bore of the reamer body, whereby its inclined or conical surface engages the ball and forces the same outwardly against the under side 5 of the cutter blade, flexing the blade longitudinally, as shown in Figs. 4 and 5, increasing the cutting diameter of the reamer.

This form and method of expanding the blades provides for a uniform and equal expansion of all of the blades, and a considerable increase in the range of expansion 10 over other methods heretofore employed.

The degree of expansion of the reamer is thus produced by longitudinally flexing the 15 blades, and the expander rod lying parallel with the blade and centrally lengthwise of the reamer body, exteriorly accessible from one end, provides a simple and compact construction. The expander rod being rotatively advanced results in a rolling motion 20 between the wedge or conical surface of the expander rod and the thrust transmitting balls, which are moved transversely during the advancing of the rod, flexing the 25 blades longitudinally and gradually with each revolution of the rod. This permits of a comparatively free adjustment of the expander rod and a uniform flexing of all 30 of the blades. The blades at their opposite ends are rounded at the base edges, allowing the blades to be flexed without injuring

the blades and clamping screws, and provide for a rolling motion or rocking action as the thrust is brought intermediately against the blades.

Having described my invention, I claim:

An expandible reamer, comprising a body having an axial bore and lengthwise peripheral cutter blade receiving recesses symmetrically disposed about the axis of the body, cutter blades respectively seated within said recesses, fastening devices for each blade removably secured into the body respectively engaging the opposite ends of a blade, a tapering expander member adjustable 45 within the bore of the body, and balls located in respective passages between the recesses and bore providing transverse thrust members between the blades and expander member for flexing the blades to expand 50 the reamer, each cutter blade having the inside edges of its opposite ends rounded adapting the blade to rock at its ends with the flexing of said blade.

In witness whereof, I hereunto subscribe 55 my name, as attested by the two subscribing witnesses.

CHARLES O. SCHELLENBACH.
